UNITED STATES PATENT OFFICE.

GEORGE ERNEST MILLER, OF MADISON, MAINE.

RECLAIMING APPARATUS FOR USE IN CONNECTION WITH PULP-MILLS.

1,156,800.

Specification of Letters Patent. Patented Oct. 12, 1915.

Application filed January 25, 1915. Serial No. 4,329.

To all whom it may concern:

Be it known that I, GEORGE E. MILLER, a citizen of the United States, residing at Madison, in the county of Somerset and 5 State of Maine, have invented certain new and useful Improvements in Reclaiming Apparatus for Use in Connection with Pulp-Mills; and I do declare the following to be a full, clear, and exact description of 10 the invention, such as will enable others skilled in the art to which it appertains to make and use the same.

My invention relates broadly to improvements in reclaiming apparatus for use in 15 connection with pulp mills and has for its object to effectively cool the acid liquor used in such devices, before it comes in contact with the gases from the digesters.

During the process of cooking the wood, 20 it is necessary to open the relief valves at the tops of the digesters to relieve the gas pressure. This gas is then conveyed through suitable pipes to the gas cooler which consists of submerged lead pipes in 25 water. From the gas cooler, the gas is passed on to the acid storage tank, this gas helping to build up the strength of the SO₂ liquor, but in many cases the gas enters the storage tank so rapidly that it heats the 30 acid liquor, thus causing it to lose a portion of its absorbing power and preventing all of the gas from combining with it. This of course causes a great waste of both gas and sulfur.

To absorb SO₂ gas freely, it is highly essential, and in fact necessary, to have the bisulfite liquor at a very low temperature. Most systems now in every day use, provide 35 amply efficient means for cooling the gases, but to my knowledge no such devices have heretofore been constructed wherein the liquor is cooled before it is brought in contact with the incoming gases.

As above set forth, it is the object of the 40 present invention to provide an apparatus whereby the acid liquor is so cooled or chilled. In carrying out this object, I provide certain novel features of construction and combination hereinafter described and 45 claimed and shown in the drawings wherein; Figure 1 is a vertical section through an apparatus constructed in accordance with my invention; Figs. 2 and 3 are horizontal sections as seen along the planes of the lines 50 2—2 and 3—3 of Fig. 1.

In these drawings constituting a part of

this application, the numeral 1 designates a vertically elongated housing or tank which may be constructed of any suitable material, comparatively hard pine wood being 60 preferably employed. The housing 1 is provided with a solid bottom 2 through which a gas inlet pipe 3 rises, said pipe carrying on its upper end a pair of crossed communicating pipes 4 which are supported upon 65 suitable sills 5 carried upon the bottom 2, these crossed pipes being perforated for the purpose of allowing the gas fed through the pipe 3, to be equally distributed through the bisulfite liquor 6, an appropriate amount 70 of which (preferably about 4 feet) is trapped in the lower end of the housing or tank 1, such liquor or liquid being maintained at this level by the provision of an outlet pipe 7 through which reclaimed acid 75 is discharged as it accumulates within the tank.

Interposed between the body 6 of the liquid, and the solid top 8 with which the tank 1 is equipped, is a plurality of horizontally disposed water inlet coils 9 whose outer ends are extended at 10 through one side of the tank and connected to an upright water supply pipe 11, while their inner ends are extended downwardly as seen 80 at 12 and connected to the inner ends of water outlet coils 13. The outer ends of these coils 13 are here shown as being extended 85 downwardly and outwardly and as connected to a water outlet pipe 14 disposed on the 90 opposite side of the tank from the pipe 11.

As clearly shown in Figs. 1 and 2, the various coils 9 and 13, are supported upon transverse bars 15 whose ends are secured to the upright wall of the tank in any appropriate manner. As likewise seen in Fig. 1, one of the bars supporting the uppermost inlet coil 9, likewise supports a cone-shaped spreader 16 which is disposed within the opening at the center of the coil. By this provision acid liquor dripping from the horizontal perforated pipe 17, disposed above sail coil 9, will be prevented from flowing through such openings of the various coils, but will be forced to drip upon said uppermost coil, it being thereby cooled to a certain extent, after which it will drip from said coil 9 to the adjacent coil 13, upon which a similar action will take place, this action being repeated a plurality of times 105 until such liquor flows from the lowermost coil 13 into the bisulfite solution already 110

accumulated at the inner end of the tank. By this means, it will be clear to those skilled in the art to which the invention relates, that such raw acid in flowing from the 5 top of the tank 1 to the bottom thereof, will be effectively chilled thereby, always reducing the temperature of the body of liquid 6, and allowing it to more readily absorb the gas flowing from the digesters and 10 charged through the perforated crossed pipes 4.

If the flow of gas to be reclaimed is so great that it is not all absorbed by the body of liquor indicated at 6, most of this gas 15 will be taken up by the cold liquid dropping from the various coils. On the other hand, in case some of this gas should reach the extreme upper end of the tank, it will be conveyed through a vent pipe 25 to an appropriate cooler or storage tank, thereby preventing it from being wasted.

I have described a horizontal pipe 17 for feeding the acid liquor into the apparatus, and in the drawings have shown such a pipe 25 as fed by an inlet pipe 17' which passes through the top 8 of the tank 1. Although this structure is ample for the purpose for which it is designed, I preferably provide valved couplings 26 at the opposite ends of 30 said pipe 17 and a valve 27 in the supply pipe 17'. By this structure, a hose (not shown) may be attached to one of the couplings 26 and the valves of both of these couplings may be opened. Then, after first 35 closing the valve 27 water may be forced through the hose thus effectively flushing the pipe 17. Although this provision is preferably made, the apparatus will operate to advantage without the same, since it is 40 very seldom necessary to clean the pipe 17 or any of the other pipes above described.

I have also described the crossed pipes 4 in the lower end of the tank 1, for the purpose of equally distributing the gas to be 45 reclaimed, through the body of liquid 6, but I have described no means whereby such crossed pipes may be cleaned or flushed should it become necessary. Since it is rather essential that such provision be made, 50 however, I have shown the ends of said pipes as equipped with valved couplings 4' which may be employed in the same manner as the coupling 26 previously described. The gas inlet pipe 3 is also shown as being 55 provided with a valve 3' whereby the passage of gas into the crossed pipes is prevented while they are being flushed.

From the foregoing description, taken in connection with the accompanying drawings, it will be seen that a comparatively 60 simple apparatus has been provided for carrying out the object of the invention, yet that such a device, although simple, will readily perform the functions for which it 65 is designed, and that such a system will

produce a more uniform and stronger acid than such systems heretofore invented.

I claim:—

1. A reclaimer for pulp mills comprising an upright housing having a perforated acid liquor inlet pipe extending horizontally across the upper end of the housing and projecting on opposite sides thereof, normally closed couplings on the opposite ends of said pipe, an acid trap at the bottom of 70 said housing, an acid discharge pipe for said trap spaced above the bottom of said housing, a gas inlet pipe into said trap, and acid liquor cooling coils disposed above said discharge pipe and below said inlet pipe. 75

2. A reclaimer for pulp mills comprising an upright housing having an acid liquor inlet at its upper end, an acid trap at its lower end, an acid discharge pipe for said trap spaced above the bottom of said housing, acid liquor cooling coils disposed between said discharge pipe and said inlet, a pair of crossed horizontal perforated gas inlet pipes extending across the lower end of the housing and projecting on opposite 85 sides thereof, and normally closed couplings on the opposite ends of said pipes.

3. A reclaimer for pulp mills comprising an upright housing having an acid liquor inlet at its top, an acid trap at its bottom, a gas inlet into said trap, a plurality of horizontal vertically spaced coils disposed between the acid liquor inlet and the trap, a cold fluid supply pipe with which the inlet ends of said coils are connected, an additional series of horizontal vertically spaced coils interposed between the first named coils and having their inlet ends connected to the outlet ends of the first mentioned coils, and a cold fluid discharge pipe with 95 which the outlet ends of the additional coils are connected. 100

4. A reclaimer for pulp mills comprising an upright housing having an acid liquor inlet at its top, an acid trap at its bottom, a gas inlet into said trap, a plurality of horizontal vertically spaced coils disposed between the acid liquor inlet and the trap, a cold fluid supply pipe with which the inlet ends of said coils are connected, an additional series of horizontal vertically spaced coils interposed between the first named coils and having their inlet ends connected to the outlet ends of the first mentioned coils, a cold fluid discharge pipe with which the outlet ends of the additional coils are connected, and a cone-shaped spreader disposed between the acid liquor inlet and the plurality of cooling coils. 110 115

5. A reclaimer for pulp mills comprising an upright housing having a perforated acid liquor inlet pipe extending horizontally across the upper end of the housing and projecting on opposite sides thereof, normally closed couplings on the opposite ends 125 130

- of said pipe, an acid trap at the bottom of the housing, an acid discharge pipe for said trap spaced above the bottom of said housing, a perforated gas inlet pipe extending 5 horizontally across the lower end of the housing and projecting on opposite sides thereof, normally closed couplings on the opposite ends of said pipe, a plurality of horizontal vertically spaced coils disposed 10 between the acid liquid inlet and the trap, a cold fluid supply pipe with which the inlet ends of said coils are connected, an additional series of horizontal vertically spaced coils interposed between the first named coils and having their inlet ends 15 connected to the outlet ends of the first mentioned coils, and a cold fluid discharge pipe with which the outlet ends of the additional coils are connected.
- In testimony whereof I have hereunto 20 set my hand in presence of two subscribing witnesses.

GEORGE ERNEST MILLER.
